PACKAGING DISPLAY KIT OR SIMILAR ARTICLE

Otto Robert Parker, New York, N. Y.

Application September 24, 1952, Serial No. 21,560

Term of patent 3½ years

(Cl. D58—2)

To all whom it may concern:

Be it known that I, Otto Robert Parker, a citizen of the United States of America, residing in New York city, county of New York, and State of New York, have invented a new, original, and ornamental Design for a Packaging Display Kit or Similar Article, of which the following is a specification, reference being had to the accompanying drawing, forming part thereof.

Fig. 1 is a front perspective view of a packaging display kit or similar article, showing my new design.

Fig. 2 is a top plan view looking into the packaging display kit.

Fig. 3 is a plan view of the packaging display kit in open position, taken on a reduced scale.

The rear view of Fig. 1 is substantially the same as shown in Fig. 1.

I claim:

The ornamental design for a packaging display kit or similar article, substantially as shown and described.

OTTO ROBERT PARKER.
